UNITED STATES PATENT OFFICE.

WILLIAM S. GUBELMANN, OF BUFFALO, NEW YORK.

KEY-INTERLOCKING MECHANISM FOR CALCULATING AND LIKE MACHINES.

1,334,533.

Specification of Letters Patent. Patented Mar. 23, 1920.

Original application filed January 10, 1900, Serial No. 1,004. Divided and this application filed August 14, 1918. Serial No. 249,905.

To all whom it may concern:

Be it known that I, WILLIAM S. GUBELMANN, a citizen of the United States, residing in Buffalo, in the county of Erie and State of New York, have invented certain new and useful Improvements in Key-Interlocking Mechanisms for Calculating and like Machines, of which the following is a specification.

10 This invention relates to improvements in key-interlocking mechanism for calculating and like machines, and is a division of my pending application Serial No. 1,004, filed January 10, 1900.

15 Only such of the mechanism herein described as refers to key interlocking mechanism is claimed herein.

One of the objects of the invention is to provide improved mechanism whereby only 20 one key of a row may be in operative position at a time.

Another object is to provide improved mechanism whereby only a predetermined plurality of keys of a row may be in operative position at a time.

Another object is to provide key-interlocking mechanism which will permit corrections to be made in the setting of the keys.

Other objects will be pointed out in the following description and claims and fully illustrated in the accompanying drawings consisting of seven sheets, in which:

Figure 1 is a fragmentary top plan view of my improved adding and recording machine.

Fig. 2 is a vertical longitudinal section of the same, taken substantially in line 2—2, Fig. 1.

Fig. 3 is a perspective view of one of the 40 registering keys.

Fig. 4 is a cross section in line 4—4, Fig. 8.

Fig. 5 is a cross section in line 5—5, Fig. 9.

Fig. 6 is a fragmentary perspective view of the gear rack and controlling arm of the 45 main adding mechanism.

Fig. 7 is a fragmentary longitudinal sectional elevation taken substantially in line 7—7, Fig. 1, and showing the auxiliary adding and printing mechanisms.

50 Fig. 8 is a fragmentary longitudinal sectional elevation taken in line 8—8, Fig. 16, and showing the mechanism whereby only one key of a row can be in depressed position at a time.

55 Fig. 9 is a fragmentary longitudinal sec-

tional elevation, taken in line 9—9, Fig. 16, and showing the mechanism whereby only a predetermined number of keys may be in a depressed position at any one time.

Fig. 10 is a fragmentary longitudinal section showing a modification of the mechanism shown in Fig. 9.

Fig. 11 is a longitudinal sectional elevation, taken substantially in line 11—11, Fig. 1, and showing particularly the paper carriage and the mechanism whereby different parts of the machine may be thrown into and out of gear.

Fig. 12 is a vertical section, taken substantially in line 12—12, Fig. 2.

Fig. 13 is a vertical transverse section taken in line 13—13, Fig. 2.

Fig. 14 is a fragmentary transverse sectional elevation taken in line 14—14, Fig. 2, and showing the mechanism for holding the 75 keys in their depressed position and for releasing the same.

Fig. 15 is a fragmentary perspective view of the key holding and releasing mechanism.

Fig. 16 is a fragmentary transverse section taken in line 16—16, Fig. 2.

Like letters of reference refer to like parts in the several figures.

General construction.

1, represents the main frame of the machine, which may be of any suitable construction so as to support the working parts of the machine.

2, represents a number of main dials which 90 register the total of the numbers which are added together. These dials consist preferably of cup-shaped wheels which are numbered on their periphery and are mounted in their proper order on a transverse dial shaft 95

3, which is journaled in bearings on the main frame, the dials being so arranged that the dial representing the lowest number is arranged on the right-hand end of the series and the dials representing the successively 100 higher numbers being arranged successively in their order toward the left from the dial representing the lowest number. The lowest or right-hand dial is preferably divided on its periphery into eighths so as to indicate fractions of a cent in eighths, and the remaining dials are graduated on their periphery according to the decimal system into tenths. As shown in the drawings ten total dials are shown and extend from fractions 105

110.

of a cent to tens of millions, but if desired, additional dials may be added to the right and to the left of the series, if it is desired to register smaller divisions of a cent, or 5 more than tens of millions. Each of the main total dials 2, is provided on its left-hand side with a gear pinion 4, which is rigidly connected therewith, as shown in Figs. 2 and 7.

10 The pinion of the fraction wheel has eight teeth, while the pinions of the remaining dials are each provided with ten teeth. 5, represents the main registering gear segments, one of which is provided for each of 15 the dials 2, and is adapted to engage with the pinion thereof, for operating the respective dial. Each of these gear segments is arranged in rear of its companion gear pinion, and is provided at its lower end with a 20 rearwardly projecting arm 6, which is pivoted loosely on a transverse supporting rod 7. This rod is mounted with its ends on the upper ends of two rock arms 8, which turn loosely with their lower ends on a transverse 25 rock-shaft 9. The rock-arms 8, are connected by a transverse bar 10, which compels the two arms to move back and forth together. In the normal position of the gear 30 segments, when the machine is at rest, these segments are retracted rearwardly out of engagement with the dial pinions of the dials and the segments are elevated so that their lowermost teeth are opposite the spaces between the adjacent teeth of the dial pinions, 35 these spaces being in line with the pivots of the pinions and the gear segments.

The gear segments are yieldingly held 40 backwardly out of engagement with the dial pinions by means of springs 11 connecting the rock-arms 8 with a stationary part of the frame. Fig. 11 shows one of the springs 11 connecting one of the rock-arms 8 with a transverse stationary bar 12 in the rear part of the machine. The gear segments are 45 moved forwardly so that their teeth engage with the dial pinions 4 by means of a shifting rock-arm 13, which is preferably secured to the right hand rock-arm 8 and projects rearwardly. Upon raising the shifting 50 rock-arm 13, the rock-arms 8 are swung forwardly and the rear segments 5 are engaged with the dial pinions, while upon swinging the shifting rock-arms downwardly, the rock-arms 8 are swung rearwardly and the 55 gear segments are disengaged from the dial pinions.

14, represents a cam whereby the gear segments are engaged with the dial pinions. This cam is mounted on the upper portion 60 of a vertically swinging rocking-frame 15, which is arranged on the right hand side of the machine. This cam is provided at its front end with an incline or cam face 16 and at its rear end with a concentric face 17. 65 When the cam is in its rearmost or retracted

position, its incline stands in rear of a roller or projection 18, on the rear end and of the shifting arm 13, as shown in Figs. 2, 7, and 12. Upon swinging the rocking frame 15, so that the cam moves forwardly, the incline 70 of the latter engages underneath the roller 18 and raises the arm 13, thereby moving the arms 8 forwardly. The throw of the incline 16 is just sufficient to engage the teeth of the gear segments with the dial pinions. 75 When the roller 18 has been raised to the top of the incline, the concentric portion of the cam engages with the roller during the continued forward movement of the cam, and the latter does not shift the gear segments any farther forward.

When the rear end of the concentric face 17 of the cam passes forwardly from underneath the roller 18, the constant pull of the springs 11 causes the rock-arm 13 to be depressed, and the rock-arms 8 to be moved rearward, thereby disengaging the gear segments from the dial pinions. Upon now moving the cam 14 backwardly together with the rocking frame 15, this cam does not affect 90 the arm 13 and the parts connected therewith, but is affected by said arm at the last portion of the backward movement of the cam, at which time the back or lower side of incline 16 engages with the roller 18 which 95 lifts said incline, and at the end of the backward movement of the cam, the latter clears said roller and drops behind the same, as shown in Fig. 2, preparatory to again raising the roller 18 and connecting parts during the next forward movement of the cam 14.

For the purpose of permitting the front end of the cam to rise so as to clear the roller 18, this cam is pivoted at its rear end to the 105 rear portion of the rocking frame 15. The upward and downward movement of the front end of the cam is limited by means of a lug 19 projecting from the side of the cam and engaging with a slot in the adjacent part 110 of the rocking-frame 15, as shown in Fig. 12.

The rocking frame 15 is secured with its lower portion to a transverse rock-shaft 20 journaled in the main frame and provided outside of the frame with a hand crank 21, 115 as shown in Fig. 12, whereby this shaft is rocked and the parts connected therewith are operated.

The gear segments 5, are raised to their highest position by means of a return or 120 lifting-bar 22, which extends transversely underneath all of the arms 6 of the gear segments and which is connected loosely at its rear ends with the transverse rod 7, by lifting plates 23.

24 represents two shifting arms which are mounted loosely at their rear ends on the rock-shaft 20, and which support at their other ends a transverse bar 25, which transverse bar is connected at its ends, by two 130

links 26, with the lifting plates 23, whereby upon raising the shifting arms 24, the lifting bar 22 is caused to raise the gear segments and the other parts connected therewith resting on said bar. Upon depressing the transverse bar 25, the lifting-bar 22 is moved downwardly, and the gear segments resting thereon are permitted to move downwardly with the bar until the segments are arrested.

Each of the gear segments is yieldingly held in contact with the lifting-bar 22 by a spring 27 which connects the arm of the segment with the transverse bar 25. If the downward movement of the gear segment is arrested while the shifting arms 24 continue to move downwardly, the lifting bar 22 is moved away from the underside of the arm of the gear segment, and the spring 27 is strained. The transverse bar 25 is arranged at one end in a segmental notch 28, formed in the front part of the rocking-frame 15, shown in Figs. 2, 7, and 12, and its opposite end is arranged in a similar segmental notch 28, formed in a rocking-frame 29 which is secured to the operating shaft 20 on the left-hand side of the machine. The rocking frames 15 and 29 together with the operating shaft 20 constitute the main or universal operating frame of the machine.

When the machine is at rest, as shown in Fig. 2, the transverse bar 25 engages with the front side of the notches 28 in the rocking frames 15 and 29. Upon turning the rocking shaft 20 forwardly by means of its handle 21, in the direction of the arrow, Fig. 2, the rocking frames are moved forwardly during the first part of the movement independent of the transverse bar 25. The latter remains at rest until the inclined front end 16 of the cam 14 has raised the arm 13 and moved the gear segments into engagement with the dial pinions, during which movement the rocking frames move idly the extent of their notches 28 along the ends of the bar 25 without disturbing the latter. After the gear segments have been engaged with the dial pinions, the continued forward movement of the rocking frames causes the rear ends of their notches 28 to engage with the bar 25 and depress the same, thereby causing the lifting-bar 22 to be moved downwardly and strain the springs 27. This causes all of the gear segments which are free, to be moved downwardly and to continue their downward movement until they are arrested. During the downward movement of the gear segments, while they are in engagement with the dial pinions, the latter and the dials connected therewith, are turned until the downward movement of the segments is arrested. The extent to which each dial is turned depends upon the position in which the downward movement of its operating segment is arrested. After the seg-

ments have been arrested in their downward movement, they remain in this position while the rocking frames complete their forward movement. At the end of the forward movement of the rocking frames, the roller 18 of the rock arm 13 drops off from the rear end of the concentric part of the cam 14, thereby allowing the springs 11 to pull the gear segments rearwardly out of engagement from the dial pinions.

75

Upon now turning the rock-shaft 20 backwardly, by means of the handle 21, the rocking frames are moved backwardly, until the front ends of the notches engage with bar 25. When the latter is so engaged it is moved backwardly with the rocking-frames to the end of their rearward movement which causes the transverse bar 25 to lift the lifting bar 22 and the gear segments which have been depressed, into their highest or normal position. During this upward movement of the depressed gear segments they are out of engagement with the dial pinions, whereby the dials are not turned backwardly with the segments, but remain in their shifted position.

80

30 represents a number of elbow-shaped controlling arms, which form part of the devices whereby the downward movement of the registering gear segments is controlled. One of these arms is arranged along the left-hand side of each gear segment and consists of an upright front part and a horizontal lower part which extends rearwardly from the lower end of the upright part, thereby leaving a clear space in rear of the upright part of the controlling lever, as represented in Figs. 1, 2, 6, and 7. The rear end of the lower part of each controlling arm is mounted loosely on a transverse supporting bar 31, while the upper end of its front or upright part is loosely connected with the upper portion of its companion gear segment. This loose connection permits the controlling arm and the gear segment to swing freely about their individual axes, which are arranged parallel but out of line, and also permits the gear segment to move forward and backward into and out of engagement with its companion dial pinion. In the uppermost position of the controlling arms the same bear with their upper ends against a transverse stop bar 32, as shown in Fig. 2, which limits the upward movement of these arms. Each controlling arm is provided on the rear part of its upper end with a locking lug 33, and on the front part of its upper end with a stop lug 34, both of which lugs project toward the left and are preferably stamped out of one piece with the controlling arm.

95

110 The operation of the registering devices is controlled by a number of elbow-shaped key levers which are arranged side by side, and pivoted to a transverse supporting rod 35.

115

120

125

130

Each key lever is provided with a lower actuating arm 36 which projects forwardly and an upper stop arm 37 which projects upwardly along the left-hand side of one of the controlling arms and gear segments, as represented in Fig. 2. Each of these key-levers is provided on the rear side of its stop arm with a locking shoulder 38 which is adapted to engage with the locking lug 33 of the controlling arm when the latter is elevated into its highest position and the key-lever is in its fully retracted position, as shown in Fig. 2. When the parts are in this position, the key-lever holds the controlling arm against downward movement and the latter holds the gear segment against downward movement. If the gear segment, while so held against downward movement is moved forward into engagement with the adjacent dial pinion, and the rocking frames are turned forwardly for depressing the gear segment, the spring 27 of this segment will be strained, without, however, shifting the segment. At the end of this forward movement of the rocking segments, the roller 18 of the rock arm 13 drops off from the rear end of the cam 14, the gear segment is moved rearwardly out of engagement from the dial pinion, and then the rocking frames move backwardly without having shifted the dial.

The upper arm of each key lever is provided on its front side with a vertical series of differential stop shoulders 39, which are arranged step fashion and extend from the upper end of this arm downwardly and forwardly thereon, or, in other words, the stop shoulders are arranged radially out of line with one another, and different distances from the pivot of the key lever. These stop shoulders of the key lever are adapted to be moved forwardly into the path of the stop lug 34 on the controlling arm. The stop shoulders are arranged different distances from the stop lug 34 of the controlling arm, so that by moving different stop shoulders of the key lever into the path of the stop lug of the controller arm, the latter, and the gear segment connected therewith, may be arrested at different points in their downward movement. The uppermost stop shoulder of the key lever is most remote from the stop lug of the controlling arm and therefore requires the greatest forward movement of the key lever, in order to bring this stop shoulder into the path of this stop lug.

The stop shoulders of the key lever are so arranged that the distance from the stop shoulders to the path of the stop lug gradually grows less from the uppermost stop shoulder to the lowermost stop shoulder. The relative position of the different stop shoulders of the key lever is such that when its locking shoulder 38 remains in engage-

ment with the locking lug 33, and the gear segment is simply moved into and out of engagement with its dial pinion, the latter remains at zero, if the same has not been previously moved. But when the key lever has been moved forwardly, so as to disengage its locking shoulder from the locking lug and moves one of its stop shoulders into the path of the stop lug of the controlling arm, the latter arm and gear segment connected therewith will be moved downwardly, upon moving the rocking frames forwardly, until the stop lug of the controlling arm strikes the respective stop shoulder of the key lever which stands in its path, whereby the gear segment, while turning in engagement with the adjacent dial gear pinion, turns the same forward. By turning the key lever forward more or less and moving one or the other of its stop shoulders into the path of the stop lug 34 of the controlling arm, the distance which this arm descends can be varied, thereby varying the number of spaces which its gear segment turns the adjacent dial.

Main number key mechanism.

40 represents the main keys whereby the key levers of the main registering and recording mechanism are operated, and which are guided with their depending stems in the top 41 and bottom 42 of the key-board. As shown in the drawings, nine longitudinal columns of these keys are arranged transversely side by side. The first column on the right hand side of the machine contains seven keys and represents fractions of one-eighth of a cent, the next column toward the left contains nine keys and represents cents, and the remaining columns of keys toward the left each contains nine keys and represents progressively higher orders of numbers according to the decimal system, so that the registering keys in the last or left-hand column, represents hundreds of thousands of dollars.

The lowest numbers of the several columns of keys are arranged transversely in a row on the rear part of the key-board, and the corresponding higher numbers of the several columns are arranged likewise in transverse rows and progressively in their order toward the front end of the key-board.

Each of the registering keys is yieldingly held in an elevated position by a spring 43 surrounding the stem of the key and connected at its upper end to the key and bearing with its lower end against the bottom of the key-board. The upward movement of each key is limited by a shoulder 44 formed on the upper part of its stem and engaging with the underside of the top of the key-board, as represented in Figs. 4, 9, 14 and 16.

The downward movement of all of the

keys is substantially the same, but the arrangement of each column of keys lengthwise of the lower actuating arm of each key lever causes the keys to bear against the lever at different distances from its pivot so that by depressing different keys the same distance, the key lever will be turned different distances. The keys having the lowest numbers bear against their respective key levers nearest the pivot and consequently the levers are thereby thrown the greatest distance, and the uppermost stop shoulders are shifted into the path of the stop lug 34 of the respective controlling arms. The throw of each key lever upon depressing any one of its keys is so adjusted, that the proper stop shoulder on its upper arm is moved into the path of the stop lug 34 of the controlling arm and the downward movement of the respective gear segment is arrested after having turned the adjacent dial gear pinion a number of spaces corresponding to the number of the key which is depressed.

Loose connection for segments.

The loose connection between each controlling arm and its gear segment, heretofore referred to, is shown in its simplest form in the connection between the controlling arm and the gear segment, which are controlled by the initial or lowest column of registering keys. As shown in Figs. 1, and 6, the loose connection between the controlling arm and the gear segment of the lowest registering device consists of upper and lower guide lugs 45 and 46 arranged on the upper end of the segment and bearing against the upper and lower guide faces 47 and 48, which are formed on the upper end of its companion controlling arm. As the controlling arm and segment rise and fall, the guide lugs of the segment slide back and forth on the guide faces of the arm. The guide faces are so constructed that the back and forth movement of the segment on the arm is radially with reference to the dial pinion in all positions of the segment. By so forming the guide faces of the arm, the gear segment can be engaged with and disengaged from the dial pinion in all positions of the segment without disturbing the position of the dial pinion. The construction of the loose connections between the controlling arms and gear segments of all of the higher registering devices above the fractional registering device are combined with carrying devices, whereby each registering dial, upon making one complete turn, causes the next higher dial to be turned forward one space, thereby carrying up a number from one column to the next higher column. The loose connections between the controlling arms and the segments and the carrying mechanism of the higher registering devices are constructed as follows:

As shown in Figs. 1, 2, and 6, each controlling arm is provided at its upper end with upper and lower guide faces 47 and 48 and its lower guide face is engaged by a lower guide lug 46 on the adjacent gear segment, the same as in the coupling between the controlling arm and segment of the initial registering device. The gear segments of the higher registering devices are each provided with an upper guide lug 49, which is adapted at times to bear against the upper guide face 47 of the companion controlling arm in substantially the same manner in which the upper guide lug 45 of the fractional gear segment bears against its companion arm, the only difference being that the upper guide lug 49 of the higher gear segments are held out of engagement and separated by a space from the upper guide face of the companion arm when no number is carried from a lower to a higher registering device. The upper guide lug 49 is held in this elevated position above the adjacent guide face by a rocking latch 50 which is arranged in a notch in the rear side of the gear segment and which normally projects toward the left and engages with the upper guide face 47 of the adjacent controlling arm, as shown in Fig. 2.

During the ordinary up and down movement of each higher controlling arm and gear segment, the latter is guided by its lower guide lug 46 and the locking latch 50 engaging with the lower and upper faces of the adjacent arm, this movement being the same as the movement of the controlling arm and gear segment of the fractional registering device. Normally the downward movement of the controlling arm is determined by the position of its companion key lever and this arm in turn controls the extent of the downward movement of the gear segment. When, however, the locking finger 50 is withdrawn out of engagement from the upper guide face 47 of the arm, the companion gear segment is capable of moving downward independent of the arm until the upper guide lug 49 engages with the upper guide face of the arm. The extent of this independent movement of the gear segment with reference to its companion arm is equal to one tooth or space of the segment, so that by this means the gear segment is enabled to turn the dial pinion one space more than the position of the key lever permits the same to move.

The withdrawal of the locking latch of each higher registering device is controlled by the next lower registering device and the withdrawal of each latch is effected when the next lower registering device has made one complete turn and arrived at zero. Each of the locking latches is pivoted on the right hand side of its adjacent gear segment, so as to turn transversely with reference to the

latter. The latch is turned toward the left into its operative position by a spring 51, the movement in this direction being limited by a shoulder 52 arranged on the latch and bearing against the right hand side of the gear segment. 53 is an upright trip plate connected with the lower end of each latch, and arranged normally at right angles, or nearly so, to the adjacent gear segment, 10 when the latch is in its operating position. 54 represents a number of upright trip arms, each of which is controlled by a lower registering device, and which turns the locking latch of the next higher registering device 15 into an inoperative position. This arm is mounted loosely with its lower end on the supporting bar 35 and is provided at its upper end with a rearwardly and forwardly projecting hook 55, and in front and below 20 said hook with a bend forming a bearing finger 56, 57 represents trip cams arranged on the left-hand side of each registering dial pinion and connected with the adjacent pinion and dial, but separated from the pinion by an intervening space or groove. The face of each of these cams may begin at its lowermost point near the axis thereof and then extend outwardly in a spiral line terminating with its highest point in line with 25 its lowermost point with which it connects abruptly. The trip cam of the fractional registering device has its face divided into eight parts, each part of which, except the first, is arranged one-eighth of a space farther from the center of the cam than the preceding part, while the trip cams of the higher registering devices each has its face divided into ten parts, each part, except the first, being arranged one-tenth of a space 30 farther from the axis of the cam than the preceding part. Each of the trip arms 54 extends upwardly along the right-hand side of the trip cam of a lower registering device and its shoulder 56 engages 35 with the face of this cam, while the hook 55 at its upper end extends toward the left and is adapted to engage with the trip plate 53 of the next higher registering mechanism. In the initial position of each trip arm, its shoulder 56 engages with the lowest part of its trip cam, as represented in Figs. 2 and 7. As the trip cam is turned in the direction of the arrow, Fig. 2, at the same time that its dial 40 and gear pinion are moved forwardly by the adjacent gear segment during the adding operation, the trip arm is moved backwardly by the gradually rising face of the trip cam. During this backward movement 45 of the trip arm, its hook engages with the trip plate 52 of the next higher registering device and is deflected toward the right thereby, the hook being sufficiently elastic for this purpose. After the hook has passed 50 in rear of said trip plate, the hook, owing to

its resilience, springs back to its normal position, so as to stand behind said trip plate. When the shoulder of the trip arm reaches the highest part of the face on the trip cam, the trip arm has been shifted to its rearmost 70 position. Upon now turning this cam forwardly another space together with its companion dial and pinion, the highest part of the cam is carried from underneath the shoulder of the trip arm and the latter is 75 moved forwardly over the abrupt face of the cam until its shoulder 56 again engages with the lowest part of the cam face. During this movement of the trip arm, its hook strikes the rear side of the trip plate 53 of the next higher registering mechanism and turns the same forwardly, thereby disengaging 80 the locking latch from the adjacent controlling arm and permitting the gear segment carrying the trip plate to move forward one space. The forward movement of the trip arm is effected when the dial with which its trip cam is connected has made one complete rotation and again stands at zero, whereby the addition represented by 85 this complete rotation is carried to the next higher registering device. The forward movement of the trip arm is effected quickly by a spring 58, which connects with a stationary cross bar 59 arranged in front 90 of the trip arms. The trip arms 53 of each registering device is so arranged and is of such length that the hook of the next lower trip arm can engage with the rear side of the plate, for disengaging its latch in any 95 position of the gear segment carrying the plate, and in order to accomplish this engagement it is obvious that cams 57 should be constructed so as to give arms 56 the proper throw. If a gear segment is locked 100 in its highest position by reason of none of its companion keys having been depressed, the withdrawal of its latch from the controlling arm simply permits the gear segment to drop one space and turn its companion dial 105 pinion forward one space, while in engagement therewith, the movement of this dial representing one number carried up from the next lower dial. If any one of the keys of the key levers has been depressed, so as 110 to release the gear segment and permit the same to move downwardly for effecting an addition, and if during this time the next lower registering device has made a complete turn, so as to require the carrying up 115 of a number from the next lower registering mechanism, the latch of the higher registering device will be withdrawn, while the same is effecting its addition, thereby causing the segment to descend and turn its dial 120 one space in addition to the spaces corresponding to the depression of its respective key.

When the locking latch has been withdrawn so as to permit a gear segment to 130

move downwardly one space farther than its controlling arm, the latch remains in this position during the subsequent upward movement of the arm and the segment until 5 the upward movement of the arm is arrested by striking the stop bar 32, and the gear segment continues its upward movement independent of the arm the extent of one space. The gear segment has now reached its highest 10 position and its latch is again swung automatically by its spring over the controlling arm. The controlling arm and gear segment now remain in this relative position until another number is to be carried 15 up from the next lower registering device.

When the controlling arm has been retracted to its highest position, the adjacent key lever is moved into its normal retracted position, so that its locking shoulder 38 engages with the locking lug 33 of the controlling arm and locks the latter against downward movement. The return movement of each key lever is preferably effected by a spring 60 which connects the 20 upper arm of the key lever with the transverse shaft 9, as shown in Fig. 2, or with some other convenient part of the machine. The lower guide lug of the gear segment is not absolutely necessary because the weight 25 of the parts connected with the controlling arm and arranged in rear of its pivot is sufficient to raise the arm, but it is preferable to employ this lower guide lug 46 on the gear segment because it compels the arm to 30 rise with the gear segment and avoids displacement of these parts with reference to each other, and also serves as a stop to limit the upward movement of the gear segment.

40 The gear pinion and the coöperating gear segment of the fractional registering device are so constructed that the fractional dial makes one rotation whenever it is moved forward eight spaces. After the fractional 45 dial has made one rotation the whole number represented by this rotation is transferred by the first carrying device from the registering mechanism of the fractional dials to the next higher registering device which 50 represents cents. The complete turns of each of the following registering devices are in like manner carried or transferred to the next higher dial by the respective carrying device. The dial which records the 55 highest number, in this instance the millions of dollars, is preferably operated only by the adjacent carrying device of the next lower dial and is incapable of being operated directly from the key-board because it 60 is not provided with a key operating mechanism.

The mechanism whereby the dials are all turned back to zero or the place of beginning, after the addition of numbers has been 65 completed is constructed as follows:

61 represents a series of feeling rock levers which are adapted to shift the key levers, so as to permit the gear segments to descend the proper distance for resetting or restoring the main registering dials to zero. One 70 of these shifting levers is mounted loosely on the supporting bar 35 adjacent to the left-hand side of each of the key levers and is provided on its upper arm with a forwardly projecting feeling finger 62 and with 75 a shifting finger 63 which extends behind the upper arm of the adjacent key lever. The feeling levers have their fingers arranged in rear of the total cams 57 and each of these levers is turned so that its upper 80 arm moves backwardly by the upper arm of the adjacent key lever engaging with the shifting finger 63 of the feeling lever. 64 represents a transverse pull bar arranged in rear of the lower arms of the feeling levers 85 and connected with each of the latter by a pull spring 65, as represented in Figs. 2 and 12. This pull bar is connected at its ends to the lower ends of two depending pull or rock arms 66, which are secured at their 90 upper ends to the rock shaft 9, as shown in Fig. 12. Upon turning this rock-shaft, so as to swing its depending pull arms backwardly, the feeling levers are turned by means of the springs 65 so as to move the 95 upper arms of these levers forwardly. This movement of the rock-shaft 9 is effected by a cam 67, which is mounted on the left-hand side of the rocking frame 29 and which is constructed substantially the same as the 100 cam 14 which is mounted on the rocking frame 15. As shown in Figs. 11 and 13, this cam is pivoted at its rear end by a transverse pin to the rear portion of the rocking frame 29 and is provided at its front end with an 105 incline or cam face 68 and in rear of the incline with a concentric face 69.

The cam 67 is pivotally supported on the rocking frame 29 in the same manner in which the like cam 14 is pivoted on its corresponding rocking frame 15.

The cam 67 can be raised and lowered with its front end into an inoperative or operative position, this movement being limited by means of a lug 70 arranged on the cam as 115 shown in Fig. 12 and projecting into a slot 71 in the adjacent rocking frame in the same manner in which the movement of the cam 14 is limited.

72, Figs. 11 and 12, represents a rearwardly projecting rock-arm secured to the rock shaft 9 and provided at its rear end with a roller or projection 73 which is adapted to be engaged by the cam 67 for turning the rock shaft 9. When numbers 120 are being added with the machine, the cam 14 is depressed, as shown in full lines, Fig. 2, so as to be in a position when moved forwardly by the rocking frame 15 to engage the roller on the arm 13, for moving the 125

gear segments into engagement with the dial pinions, and during this time the cam 67 is lifted into the position shown in full lines, Fig. 11, so that when the rocking frame 29 is moved forwardly, the cam 67 will clear the roller 73 of the rock-arm 72 and not disturb the rock-shaft 9 and the parts connected therewith.

If it is desired to restore all of the total 10 dials 2 to zero, the cam 14 is raised into its inoperative position, shown by dotted lines 14 in Fig. 2, and the cam 67 is lowered into its operative position, as shown by dotted lines 67^a in Fig. 11. Upon now turning the 15 rock-shaft 20 by hand so as to move both rocking frames 15 and 29 forwardly, the cam 14 passes over the roller 18 of the arm 13 without disturbing the same, but the inclined front of the cam 67 engages with the 20 roller 73 on the rear end of the rock-arm 72 and raises the same until this roller engages with the concentric part 69 of this cam. By this movement of the arm 72, the rock-shaft 9 is turned in the direction for moving its 25 depending arms 66 rearwardly and pulling the springs 65 rearwardly. This pull on the springs 65 causes the feeling levers to be turned until the feeling fingers of their upper arms engage with the spiral surfaces 30 of the trip cams. After the feeling fingers bear against these cams, their movement is arrested and the continued backward movement of the pull bar 64 simply stretches the springs 65 until the bar reaches the end of 35 its backward movement. The feeling finger of each feeling lever engages with that part of the surface of the adjacent trip cam which is directly opposite the feeling finger, and as these trip cams are turned with the adjacent dial they present different parts of 40 their spiral surfaces to the opposing feeling fingers, which causes the forward movement of the upper arms of the feeling levers to be arrested in different positions when 45 swung forwardly. During the forward movement of the upper arm of each feeling lever, its shifting finger 63 engages with the rear side of the upwardly projecting arm of the adjacent key lever and moves this arm 50 forwardly. The construction of the parts is such that the spiral surfaces of the trip cam bear a definite relation to the step-shaped series of stop shoulders on the upper arm of the key lever. When the feeling 55 finger of the feeling lever, upon being moved forwardly, bears against the lowest key-lever-stop-controlling part of the adjacent trip cam, the adjacent key lever is carried simultaneously forward with the feeling lever the greatest distance and its uppermost stop shoulder is carried into the path of the stop lug of the controlling arm. The 60 succeeding parts of the spiral surface of the trip cam are so constructed that they rise 65 progressively higher and arrest the forward

movement of the feeling lever when the same has carried the adjacent key lever with its corresponding stop shoulder into the path of the stop lug of the controlling arm. This forward movement of the feeling lever 70 and that of the upper arm of the key lever is gradually reduced as the progressively higher parts of the trip cam are presented to the feeling finger, and when the highest part of the trip cam is presented to the feeling finger, the feeling lever is prevented from moving forward at all and the upper arm of the key lever is not moved with its locking shoulder out of engagement with the locking stop of the controlling arm and 75 consequently the companion gear segment connected therewith is held against downward movement. After the rocking frames 15 and 29 have been turned forwardly sufficiently to engage the several feeling fingers 80 of the feeling levers with their respective trip cams, the rear ends of the segmental notches 28 in the rocking frames engage with the cross bar 25 and depress the same, thereby moving the lifting-bar 22 downwardly, and at the same time pulling down the springs 27. This downward pull on these springs causes each spring to pull its respective gear segment down as far as possible, and after the downward movement of 85 the segment has been arrested the continued downward movement of the cross-bar 22 together with the rocking frames simply stretches these springs until this bar reaches the end of its downward movement. If a 90 gear segment is locked in its uppermost or zero position its spring 27 will be stretched its fullest extent, whereas, if a gear segment moves downwardly more or less before it is arrested by its shifted key lever, its spring 95 100 105 110 115 120 125 130 27 will be stretched less in proportion. This downward movement of the gear segments which are free to move in this direction takes place while the gear segments are in their retracted position and out of engagement from the dial pinions, so that the dials are not affected by this movement of the segments.

After the rocking frames have reached the end of their forward movement and the roller 73 has dropped off from the rear end of the concentric portion 69 of the cam 67, the gear segments are moved forwardly by hand-operated mechanism into engagement with their respective dial pinions and are held in this position during the entire subsequent backward movement of the rocking frames, which is effected by hand-operated mechanism. During the backward movement of the rocking frames, the gear segments are raised to their highest positions, while in engagement with the dial pinions by the rod 22 and connecting parts and turn the dials backwardly. At the end of the upward movement of the gear segments the 130

latter are released, so as to permit them to move into their retracted position, out of engagement from the dial pinions.

During this operation, those gear segments which are held or locked in their highest positions, by reason of their dials being at zero, are simply moved forward at the end of the forward movement of the rocking frames, so as to engage with their respective dial pinions and are again moved backwardly out of engagement therefrom at the end of the forward movement of the rocking frames, without disturbing their respective dials. Each of the unlocked gear segments is moved downwardly a number of spaces corresponding to the number which is registered on its dial, the extent of this movement being controlled by the companion trip cam which arrests the forward movement of the key lever, through the medium of its feeling lever, when the proper stop shoulder of the key lever has been presented to the controlling arm.

Upon now moving the gear segments forwardly in their variously depressed positions and then raising them to their highest position, each depressed gear segment will turn its dial backward the same number of spaces that the gear segment was depressed. Inasmuch as each gear segment was permitted to descend by its trip cam, feeling lever and key lever, the same number of spaces as the number indicated on its dial, the gear segment subsequently moves upwardly the same number of spaces before reaching its highest position, thereby turning its dial backwardly the same number of spaces and restoring the same to zero. When all of the dials have been returned to zero, the shoulders 56 of all the trip arms engage with the lowest parts of all the trip cams 57.

The cams 14 and 67 are provided with a longitudinal slit 74, so as to facilitate the manufacture of these parts.

The mechanism whereby the positions of the cams 14 and 67 are reversed preparatory to restoring the dials to zero is constructed as follows:

The cams 14 and 67 drop into their operative position by gravity. Each of these cams is provided in rear of its pivot with a tail 75 which is depressed when it is desired to lift the respective cam into its inoperative position.

76, is a shifting lever which is pivoted at its lower end and is normally turned so that its upper end is disengaged from the rear side of the tail on the cam 14 by a spring 60 77, as shown in Fig. 2. The member 76 projects in rear of the main frame so as to be accessible for manual operation.

Each of the dials is held against turning while its companion sub-total dial is being

turned to zero by means of a detent pawl 65 103 which engages with the front side of its companion gear pinion, as shown in Figs. 2, 7, 9, and 18. The pawls 103 of the several gear pinions are mounted on a transverse pawl bar 104, which is supported at its ends 70 by means of two pawl arms 105, which turn loosely upon the supporting rod or bar 35 of the key levers. The pawl arms are moved rearwardly for engaging the pawls of the bar 104 with the gear pinions by 75 means of springs 106. These springs are connected loosely at their rear ends to the rock-shaft 9 and at their front ends to the pawl arms 105. During the forward movement of the gear segments preparatory to 80 turning the dial pinions, the detent pawls are swung forwardly out of engagement with the dial pinions by means of two shifting rods 107 which are connected at their rear ends to opposite ends of the transverse 85 rod 7 or some part moving therewith, and each of which is provided at its front end with a fork or bifurcation 108, which engages with a pin or shoulder 109 on the pawl arm arranged on the adjacent side of 90 the machine. As the gear segments move forward into engagement with the gear pinion the shifting rods 107 move the detent pawls 103 out of engagement with the dial pinions and when the gear segments move 95 backwardly the detent pawls are again engaged with the dial pinions by the springs 106.

Recording mechanism.

For the purpose of recording the numbers which are added together by the above described mechanism, a recording mechanism is provided, which is constructed as follows:

140 represents a printing roller or platen which is arranged transversely in the upper, rear part of the machine and under the lower side of which the sheet or other article is placed which receives the record. 141 110 represents a number of type segments which are arranged transversely side by side below the platen and which are pivoted at their front ends to the supporting bar 31 upon which the rear ends of the controlling 115 arms 30 are pivoted. Each of these type segments is provided at its rear end with a segmental row of type-carriers 142, which are capable of moving radially back and forth on the type segment.

120 Each of the type carriers is provided at its rear end with a type and is guided upon the type segment by means of screws or rivets 143 secured to the type carrier and arranged in radial slots 144 formed in the 125 type segment, as shown in Figs. 2 and 3. Each of the type carriers is held in its inward or retracted position by means of an

S-shaped spring 145, which is arranged between the carrier and the type segment and is secured with one end to the carrier and with its other end to the type segment. 5 Upon raising or lowering the type segment any one of its type can be brought to the printing point or line, and upon striking the back or inner end of the type carrier, when the same is in line with the printing 10 point the type carrier will be driven outwardly and its type will produce an impression on the sheet supported by the platen. After the carrier has received the blow for driving the same against the platen, the carrier is again quickly retracted to its innermost position by means of its spring. 15

Each of the type segments is connected with one of the controlling arms, so that upon depressing a controlling arm and the 20 registering gear segment connected therewith, the companion type segment will be raised and present one of its type to the printing point.

For convenience in operating the machine, 25 the keys are separated a considerable distance on the key-board and in order to produce a compact record, the printing segments are arranged closer together than the keys and the registering mechanism. In order 30 to permit of this arrangement, each type segment and its controlling arm are connected by a connecting arm 146, as represented in Figs. 1 and 2. The connecting arms of the central controlling arms and 35 type segments are comparatively straight, but the connecting arms of the outer type segments and controlling arms are arranged obliquely, the degree of this obliquity gradually increasing from the central type segments and controlling arms in opposite directions toward the outer type segments and controlling arms, as represented in Fig. 1. The connecting arms 146 of the outer controlling arms are arranged in the spaces behind the upright parts and above the horizontal parts of the controlling arms, thereby 45 permitting the inner controlling arms to move up and down without interfering with the connecting arms 146 of the outer controlling arms. 50

The types on each type segment are arranged to correspond with the teeth and numbers of its companion gear segment and registering dial, the zero type being at the 55 upper end of the series and the progressively higher digits arranged in their order downwardly from the zero type. When the registering gear segment is in its highest position it presents its zero tooth to the dial pinion, and the type segment, which at this 60 time is in its lowest position, presents its zero type to the printing point. Upon depressing a gear segment so as to present one of its higher teeth to the dial pinion, its companion type segment is raised proportion-

ally and presents a corresponding higher numbered type to the printing point.

147 represents a number of hammers whereby the type-carriers are struck for driving the type against the platen. One 70 of these hammers is arranged adjacent to each type segment and is provided with a head which is arranged in front of the series of types and in line with the printing point of the platen. Upon shifting the type segment so as to bring one or another of its type carriers to the printing line and then operating the hammer, the latter delivers a blow against the inner end of the particular carrier which is at the printing point and 75 produces an impression of its type on the platen. The several hammers are pivoted on the transverse rod 12, arranged in rear of the segments; and each of the hammers is yieldingly held in its forward position by a 80 spring 148 connected at its lower end to a cross-bar 149 and at its upper end to a depending arm 150 on the hammer.

151 represents a vertically movable trip bar or rod which is arranged transversely 90 below the hammers and whereby the hammers are operated. This bar is supported at its ends upon the rear ends of rock arms 152 which turn loosely with their front ends on the rod 31 supporting the type segments 95 and controlling arms.

153 represents a number of hammer or trip pawls, whereby the hammers are retracted preparatory to delivering a blow against the type carriers which are at the 100 printing point. One of these pawls is arranged adjacent to each hammer and pivoted loosely at its lower end to the trip bar 151, and its upper end is provided on its 105 rear side with a downwardly facing hook or shoulder 154, and above this shoulder with a trip face 155. Each of the hammers is provided in front of its pivot adjacent to the upper end of the hammer pawl with a lower trip lug or shoulder 156 and an 110 upper trip lug or shoulder 157. When the parts are at rest, the hammer pawl 153 is raised into its highest position and the hammer is in its normal position with its lower trip lug 156 below and in rear of the hook 115 of the hammer pawl and with its upper shoulder 157 in rear of the trip face of the hammer pawl, as represented in Fig. 2.

Upon shifting the hammer pawl rearwardly, while the parts are in this position, 120 so that its hook overhangs the lower shoulder 156 of the hammer, and then pulling the hammer pawl downwardly, the hook of the hammer pawl engages with the lower shoulder of the hammer and turns the same 125 so that its head is retracted from the type carrier at the printing line. As the hammer moves downwardly with the hammer pawl, the upper shoulder of the hammer comes into engagement with the trip face of the 130

hammer pawl and during the continued downward movement of the hammer and its pawl, this upper shoulder gradually crowds the hammer pawl forwardly with reference 5 to the hammer by reason of the hammer and its pawl swinging on different centers. During the last portion of the downward movement of the trip bar 151 and the hammer pawl mounted thereon, the pawl is 10 crowded forwardly by the upper shoulder 157 of the hammer to such an extent that its hook is disengaged from the lower shoulder 156 of the hammer, thereby liberating the latter and permitting its spring 148 to 15 throw the same quickly and deliver a blow against the type carrier at the printing line. The trip bar 151 now rises and carries the hammer pawl into its highest position, preparatory to again engaging the hammer for 20 depressing the same.

158 represents a number of upright shifting arms whereby the hammer pawls are moved rearwardly, so that their hooks engage with the lower shoulders of the hammers. One of these arms is arranged adjacent to each hammer pawl, and is pivoted at its lower end on the trip bar 151, and its upper end is provided with a roller or projection 159 which bears against a hammer cam 160 on the lower part of the adjacent type segment. This hammer cam is provided at its upper end with a receding or low portion, an inclined portion arranged below the low portion, and a concentric or 35 high portion arranged below the inclined portion. Each shifting arm 158 is moved forwardly and its roller is yieldingly held in engagement with the adjacent hammer cam by a spring 161 connecting said arm 40 with a cross bar 162 secured to the rock arms 152. The backward movements of each hammer pawl with reference to its companion shifting arm, is limited by means of a stop 163 secured to the upper portion of 45 the hammer pawl and engaging with the front side of the shifting arm.

Each hammer pawl is yieldingly held in its rearmost position with reference to its shifting arm by means of a C-shaped spring 50 164 secured with its ends, respectively, to the hammer pawl and its shifting arm, as shown in Fig. 2.

In the lowermost position of a type segment, the receding part of its cam is presented to the roller of the shifting arm 158, which permits the hammer pawl to be retracted into its foremost position, as represented in Fig. 2. Upon depressing the trip bar 151 when the parts are in this position, the roller 159 is not engaged soon enough by the incline of the cam 160 to engage the hook of the hammer pawl with the lower shoulder of the hammer, before the hook has passed below this shoulder; 60 but instead, the trip face of the hammer

pawl slides idly against the shoulder 156 without retracting the hammer, whereby no impression of the particular type at the printing line is produced. If the type segment is raised, so as to present one of its 70 lower types to the printing point or line, the incline of its cam, during the first part of the upward movement of the segment, moves the shifting arm 158 rearwardly together with the hammer pawl yieldingly 75 connected therewith, so that the hook of the hammer pawl stands over the lower shoulder 156 of the hammer. Upon now depressing the pawl 153 the hammer will be retracted and released near the end of the 80 downward movement of the pawl, and will be quickly swung up by the spring 148, thereby delivering a blow against the type at the printing point and producing an impression thereof.

85 The incline 160 of the type segment cam is so constructed that it throws the hammer pawl backwardly into an operative position when the segment is raised one digit space, and during the continued upward movement of the segment, the hammer pawl is held in this operative position by the high concentric part of the segment cam. By thus constructing the type segment cam its companion hammer pawl is not 90 shifted when the segment is not raised and its zero type remains at the printing line, but the hammer pawl is shifted into an operative position for producing an impression, if the type segment is raised one or 95 more digit spaces and presents any one of its digits higher than zero to the printing line.

Automatic printing of zero.

100 165 represents a number of transfer or coupling fingers which enable the ciphers in a number to be printed automatically. One of these transfer fingers is secured to each of the shifting arms 158, and extends laterally toward the right therefrom into engagement with the shifting arm of the next lower hammer pawl, as represented in Fig. 13. If any one of the printing segments remains in its lowest position, so that its 110 cipher remains at the printing line and the next higher printing segment has been raised for printing a higher number or digit, the transfer finger of the higher hammer shifting arm 158 while being moved rearwardly by the cam of its companion printing segment, is caused to engage with the shifting arm 158 of the next lower hammer pawl and shift the latter backwardly, so that its hook is carried backwardly over the 115 lower shoulder of the companion hammer. Upon now depressing the trip bar 151, the higher hammer pawl 153 is coupled with its hammer, and the next lower hammer pawl is also coupled with its hammer, whereby 120 125 130

an impression of the cipher or zero type on the lower segment is produced on the platen at the same time that the next higher number is printed on the platen.

- 5 If two ciphers occur in succession in the body of a number, the shifting arm to the left of the highest order printing segment to be operated for printing a zero sets the hammer mechanism of said highest zero-
10 printing segment by means of the transfer finger of said shifting arm and the shifting arm of said highest zero-printing segment in turn, by means of its transfer finger, sets the hammer mechanism of the printing segment
15 of next lower order, etc.

This operation of producing an impression of the cipher type is effected automatically and renders it possible to print any number of ciphers in succession in the body
20 of a number because the hammer operating mechanism of each segment which remains standing with its upper type at the printing line is controlled by the hammer operating mechanism of a higher type segment
25 and in turn controls the hammer operating mechanism of the next lower type segment, if the next lower segment presents a cipher to the printing line.

Only the ciphers below the highest digit
30 in the number to be recorded are thus printed automatically because the printing of a digit depends upon the upward movement of a printing segment, thereby avoiding the printing of ciphers ahead of the highest digit in the number to be recorded. The hammer shifting device of the segment which prints the numbers representing units of cents is, preferably, not provided with a transfer finger to operate on the hammer
35 shifting device of the segment which prints fractions of a cent, because it is proper that the space to the right of the lowest integer shall remain blank when no fraction is recorded thereon.

40 45 The carrying bar 151 is raised by one or more springs 166 which connect this bar with the transverse rod 12, and the upward movement of the bar 151 is arrested when the hammer operating pawls reach their highest position by a transverse bar 167 which is engaged by the rear ends of the rock arms 152.

168 represents a coupling hook, whereby the hammer trip devices are depressed.
50 55 This hook is pivoted with its upper end to the trip bar 151 and its lower engaging end is provided with a notch having upper and lower shoulders.

In the lowered position of this hook its
60 notch engages with a cross-bar 169 which is connected with the rock arms 24, as represented in Fig. 2, so that the hook and the hammer operating devices connecting therewith are actuated from the rocking frames

15 and 29, through the medium of the rock 65 arms 24. In the rearmost position of the rocking frames, the front ends of their notches 28 bear against the front side of the bar 25 to which the gear segments are yieldingly connected, and the cross bar 169 bears 70 against the rear or upper shoulder of the notch of the hook 168, as represented in Fig. 2.

Upon swinging the rocking frames forward, the incline of the cam 14 first raises 75 the rock arm 13 and shifts the gear segments into engagement with the dial pinions, and after the segments have been so shifted, the rear shoulders of the notches 28 in the rocking frames engage with the 80 crossbar 25, so that thereafter this bar is carried downwardly with the rocking frames and the gear segments are depressed. During this downward movement of the bar 25 with the rocking frames, the companion bar 85 169 moves down idly in the notch of the hook 168 until this bar engages with the lower or front shoulder of this hook. After the cross bar 169 engages with the lower shoulder of the notch of the hook, the latter 90 and the hammer-operating devices connected therewith are moved downwardly with the rocking frames until these frames reach the end of their downward movement. During the last portion of the downward movement 95 of the rocking frames the hammer pawls are disengaged, as before described, from the retracted hammers, whereby the latter are released and strike the type-carriers which are at the printing line. By this means, the 100 blow of the hammers is delivered after the registering of the numbers has been effected on the dials and the type segments have been shifted into their proper position for recording the respective number.

105 The hammers do not follow the type-carriers to the end of their outward movement but are stopped short, after delivering a blow against the inner ends of the carriers by their depending arms 150 engaging with a 110 rubber facing 170 on the cross-bar 167, so that the types are moved outwardly by the impact of the hammers and are then returned by their springs so as to clear the printing surface.

115 When it is desired to print or record the total at the foot of the column of the numbers which have been printed, the operation is as follows:—The total key 84 is first depressed, thereby raising the cam 14 into an 120 inoperative position and lowering the cam 67 into an operative position. Upon now moving the rocking frames 15 and 29 forwardly the feeling levers 61 are turned so as to move their feeling fingers forwardly 125 into engagement with the respective cams 57 and at the same time each feeling lever carries the adjacent key lever forwardly

so that its particular stop shoulder 39 corresponding to the position of the trip cam 57 and its dial is moved into the path of the stop lug 34 of the controlling arm. After 5 the key levers have been thus shifted forwardly into their respective positions corresponding with their dials, the continued forward movement of the rocking frames causes the gear segments, while in a retracted position out of engagement with the 10 dial pinions, to be depressed until each segment is arrested by the engagement of the stop lug on its controlling arm with the respective stop shoulder of its key lever, 15 whereby each printing segment is raised so as to present the type carrier to the printing point which carries the type corresponding to the number registered on its companion dial. During the last part of the forward 20 and downward rocking movement of the rocking frames the hammers are operated and the particular type at the printing line are impressed on the platen.

Upon now swinging the rocking frames 25 backwardly, the gear segments are raised while still in a retracted position out of engagement with their companion dial pinions, thereby permitting further numbers to be added to the total already registered 30 on the dials. If, however, it is desired to turn the dials back to zero, after the total of the added numbers has been printed or recorded, the gear segments, while in the retracted lower position which they occupy 35 while printing the totals, are moved forwardly into engagement with their respective dial pinions by the depression of the key 87. Upon now moving the rocking frames backwardly, the gear segments are 40 raised, while in their forward position in engagement with their pinions, whereby each of the latter is turned backwardly and when the segments reach the end of their upward movement, the dials have been turned backwardly 45 a number of spaces corresponding to the number on the dial, thereby turning all of the dials to zero.

Auxiliary adding mechanism.

50 An auxiliary adding mechanism is provided which permits of effecting an addition of numbers different from the numbers which are added by the main adding mechanism. 55 This auxiliary adding mechanism is constructed as follows:—2000 represents a number of auxiliary dials which are mounted on the left hand end of the dial shaft 3. 5000 represents a number of auxiliary gear 60 segments which are mounted on the transverse rod 7 and are adapted to engage with gear pinions 400 on the auxiliary dials, as represented in Fig. 7. Each gear segment 5000 is connected with a controlling

arm 3001 arranged adjacent to the gear 65 segment by a latch or coupling which at times permits the segment to move independently of the controlling arm.

3601 and 3701 represent auxiliary key levers which are operated by auxiliary keys 70 401 and which control the operation of the auxiliary registering and recording mechanism. The detail construction of the dials, gear segments, printing segments, key levers, and the parts coöperating therewith of the 75 auxiliary registering and recording mechanism is substantially the same as the construction of the same parts in the main registering and recording mechanism, except as hereinafter distinguished, and the same letters of reference are therefore employed to denote like parts in both of these sets of mechanisms.

In the drawings, two auxiliary key levers 85 and three auxiliary dials are shown, which permit of registering and recording a total of 999, but additional registering and recording devices may be employed if it is desired to increase the capacity of the machine. 90

In the auxiliary mechanism each of the higher gear segments 5000 is provided with a pivot latch 501 the same as in the main registering mechanism. The lowest or primary gear segment of the auxiliary registering mechanism is provided with a movable latch 502 which is adapted to be engaged with or to be disengaged from the upper guide face on its companion controlling arm, but for the purpose of the present application this latch might be dispensed with and the primary gear segment constructed 100 the same as the primary gear segment of the main registering and recording device. 95

In the auxiliary registering mechanism 105 the gear segments are not provided with lower stops 46 like those of the gear segments of the main registering mechanism which permits the auxiliary controlling arms to move downwardly when necessary 110 independently of the auxiliary gear segments. The upward movement of the auxiliary gear segments is limited by stops 218 with which the upper ends of the gear segments engage. 219 represents a foot formed 115 on the lower side of each controlling arm 3001 and adapted to engage with the lifting cross-bar 22. However, for the purpose of the present application, the auxiliary mechanism could be made exactly as the main 120 number registering and recording mechanism is made.

For the purpose of effecting an ordinary addition of numbers on the auxiliary registering mechanism, the auxiliary key levers are shifted into the proper position by the depression of the keys 401 representing the numbers to be added and then the rock-

125

ing segments 15 and 29 are turned forwardly. During the forward movement of the rocking frames the auxiliary gear segments are first moved into engagement with the auxiliary dial pinions by the cam 14 and then pulled down by the springs 27, and the controlling arms are also pulled down by the latches of the gear segments engaging with the controlling arms. The downward movement of the gear segments and controlling arms continues until the stops 34 of the controlling arms strike the shoulders 39 on the key levers which stand in the path of the stops 34. At the end of the forward movement of the rocking frames the gear segments are withdrawn from the dial pinions by the springs 60 and during the subsequent backward movement of the rocking frames, the gear segments and controlling arms are raised by the cross-bar 22 engaging with the gear segments and with the feet 219 of the arms. The carrying of numbers from the units dial to the tens dial and from the latter to the hundreds dial and the turning of the dials to zero is effected in the same manner as in the main registering mechanism.

By this organization of the machine, numbers such as sales or pieces of goods can be added and recorded by the main registering mechanism and other numbers such as the rebate on sales or discount on the prices of goods, can be separately added or recorded by the auxiliary registering mechanism. The key controlled devices whereby the parts of the main registering and recording mechanism are shifted into the proper position preparatory to registering and recording a number are distinct from the key controlled devices whereby the same effect is produced in the auxiliary registering and recording mechanism, but both sets of registering and recording mechanisms are operated simultaneously by the one universal shifting mechanism for effecting the registration and recording of the numbers which are represented by the different positions of both key controlled devices.

Keyboard mechanism.

The keys which have been depressed in the operation of adding or recording a number are automatically locked in a depressed position until the adding or recording operation of the particular number has been completed, and then the depressed keys are automatically released and permitted to be raised by their springs.

As shown in Figs. 2, 4, 5, 7, 11, 14, 15, and 16, the keys are held in a depressed position by a number of locking plates 327, one of which is arranged lengthwise on the left side of the stems of each row of keys. Each of the locking plates is pivoted at its lower end to the top of the keyboard bottom, so as

to swing transversely and is provided along its upper edge with a number of downwardly facing catches or shoulders 328 which are adapted to engage with upwardly facing locking shoulders 329 on the stems of the keys. Each of the keys is provided with a convex face below its locking shoulder, consisting of a lower rising portion 330 which inclines upwardly and laterally from the lower part of the key toward the adjacent locking plate, and an upper receding portion 331 which inclines from the upper end of the rising portion to the outer end of the locking shoulder 329 of the stem, as shown in Figs. 5, 15 and 16. Each locking plate is drawn yieldingly with its catches against the stems of the adjacent rows of keys by a spring 332, as shown in Figs. 9 and 16. The locking catches of the locking plates bear against the key stems below the convex faces thereof when the keys are in an elevated position, as shown in Fig. 14. Upon depressing a key, the convex face on its stem deflects the locking plate, and when the key has been depressed fully the respective locking catch of the locking plate engages with the locking shoulder 329 of the stem of the depressed key, thereby retaining the parts which are operated by said key in a shifted position.

If a wrong key has been depressed and the operator subsequently depresses the right key, the latter, during the first part of its downward movement, engages the lower or rising part 330 of its convex face with the adjacent locking catch of the locking plate and disengages the respective locking catch from the locking shoulder of the previously depressed key, thereby releasing the same, as represented in Figs. 4 and 5. Upon continuing the depression of the second or correct key after the first or wrong key has been released, the receding or upper part 331 of the convex face of the correct key engages with the adjacent locking catch of the locking plate, thereby permitting the latter to approach the key stem and when the correct key has been fully depressed its locking shoulder is carried below the locking catch of the plate and is engaged thereby, whereby the correct key is locked in a depressed position. By this means any incorrectly depressed key is automatically released by the depression of the correct key, and the latter is in turn automatically locked in a depressed position.

Automatic key release.

333 represents a transversely movable releasing bar, whereby the keys of the main number-registering devices are released. This bar is arranged transversely in rear of the rear ends of the locking plates of the main number-keys and is guided with its ends in the frame of the machine, as shown

in Fig. 14. This bar is provided with a number of upwardly projecting releasing lugs or shoulders 334, one of which is adapted to engage with the right side of a 5 pin or projection 335 on the rear end of each locking plate of the main registering keys, as represented in Fig. 14. Upon shifting the releasing bar 333 toward the left, its releasing lugs move the main locking plates 10 in the same direction, thereby releasing any number-keys which are held in a depressed position by the same.

The main releasing bar 333, when free, is shifted toward the right into its retracted 15 position by the resilience of the springs which hold the main locking plates in their operative position.

The releasing bar 333 is shifted into its operative position by a releasing elbow lever 20 336 which turns on a pivot pin 337 and is connected with its upwardly projecting arm with the releasing bar 333 while its lower arm projects horizontally outward. 338 represents a releasing arm which is arranged 25 lengthwise in the machine and transversely over the lower arm of the releasing elbow lever 336 and which is pivoted at its front end on a pin 339, as represented in Figs. 11, 14, and 15. 340 represents a longitudinal releasing lever connected by an upright cord 341 with the rear end of the releasing arm 338 and projecting with its rear end into the path of the cross bar 25, as represented 30 in Fig. 11.

35 The main number keys are held in their depressed position until the rocking frames 15 and 29 have been moved forwardly sufficiently to operate the registering and recording mechanisms in accordance with the 40 numbers of the depressed main keys and then the cross-bar 25, during the last part of its forward movement with the rocking frames 15 and 29, engages with the releasing lever 340 and depresses the same. The 45 releasing arm 338, during its downward movement with the releasing lever 340, engages with the lower arm of the elbow lever 336 and turns the latter so that its upper arm moves the main releasing bar 333 toward the left and moves the main locking plates 50 out of engagement with the main number-keys, thereby releasing the depressed main keys and permitting them to rise preparatory to setting the machine for 55 registering and recording the next number.

Each row of auxiliary keys 401 is provided with a locking mechanism similar to those of the rows of main number keys.

The several shifting keys are arranged in 60 a longitudinal row or column on the left side of the auxiliary keys, and the elbow levers operated thereby are arranged one behind the other, as represented in Figs. 11, 14 and 15.

65 342 represents an auxiliary releasing bar

whereby the locking plates of the auxiliary keys are released. This bar is arranged transversely of the machine, in front of and parallel with the main releasing bar 333 and is adjustably connected therewith, so that 70 the auxiliary releasing bar can be moved into an operative or inoperative position on the main releasing bar.

As shown in Fig. 14, the auxiliary releasing bar is pivoted at its inner end to the 75 main key-releasing bar by a horizontal pivot, and its outer end projects through an opening 343 in the frame, which permits this bar to be manipulated by the operator from the outside of the frame. The auxiliary releasing bar is held in its raised or lowered position by means of two notches or recesses 80 344, 345, formed one above the other in this bar, and each of which is adapted to be engaged with a pin or projection 346 on the 85 main releasing bar, as shown in Fig. 14, by the resilience of the auxiliary releasing bar which is sufficiently elastic for this purpose.

Upon raising the auxiliary releasing bar 90 and engaging its lower recess with the pin 346, the releasing lugs 347 of this bar are carried in front of the right side of the pins on the rear ends of the locking plates of the auxiliary keys, so that upon moving the 95 main releasing bar toward the left for releasing the main keys, the auxiliary releasing bar is simultaneously moved in the same direction and disengages the locking plates from the auxiliary keys. When it is desired 100 to register or record an arithmetical progression of a number the auxiliary releasing bar is depressed, so that its lugs 347 are below the pins of the locking plates of the auxiliary keys, this bar being held in this 105 position by engaging its upper recess 344 with the pin 346. Upon now depressing the auxiliary keys of the desired number and then operating the registering and recording mechanism the number represented by the 110 depressed keys will be registered and recorded, but these keys will not be released. While the depressed keys are thus held in a depressed position, the registering and recording mechanism can be repeatedly operated, during each of which operations the number represented by the depressed key is added over and over again, thereby registering and recording the arithmetical progression of this number.

115 The column or row of shifting keys is provided with a locking mechanism similar to the main and auxiliary keys, but the locking plate of the shifting keys is disengaged from the stems by a separate releasing 120 mechanism so as to permit the main and auxiliary number keys to be released without releasing the shifting keys.

125 As shown in Figs. 14 and 15, the release of the shifting keys is effected by a 130

supplemental releasing-bar 348, having lugs 349, one of which engages with the pin 335 on the rear end of the locking plate of the shifting keys and which is guided at its 5 outer end in the frame. The inner end of the supplemental releasing-bar is pivoted to the upper arm of a releasing elbow lever 350. This lever is pivoted on the pin 337 and its lower arm projects toward the right and underneath the releasing arm 338 adjacent to the rear side of the lower arm of the releasing elbow lever 336.

When both lower arms of the releasing elbow levers 336 and 350 are arranged underneath the releasing arm 338, the depression of the latter by the rocking frames causes the supplemental releasing bar to be moved toward the left so that its lug disengages the locking plate of the shifting keys 10 from their respective stems at the same time that the main and auxiliary releasing bars disengage the locking plates of the main and auxiliary number-keys from their respective stems, thereby releasing all of the 15 keys simultaneously after the registering and recording of the numbers has been effected.

When it is desired to record the total of the added numbers or when it is desired to 20 return the dials to zero, the number keys must all be released in order to permit the key levers to assume a position corresponding to the dials preparatory to recording the total registered by the same. This is effected 25 by an intermediate elbow lever 358 which is pivoted on the pin 339 and which projects rearwardly over the lower arm of the releasing elbow lever 336 but does not project over the lower arm of the releasing elbow lever 30 350, as shown in Figs. 14 and 15. 359 represents a longitudinal connecting-bar connected at its rear end to the lower arm of the intermediate elbow lever 358 and provided with longitudinal slots 360 which receive pins or projections 361 on the lower 35 arms of the elbow levers 118, 177, 80 and 85 and which are operated by the keys 84, 181, 87, and 120 (as shown in Fig. 11). The pins 361 engage normally with the front ends of 40 their respective slots in the connecting bar 359 which causes the latter to be shifted forward by any one of the respective keys without disturbing the others. Upon moving the connecting-bar 359 forwardly by the 45 depression of any one of the keys 84, 181, 87, or 120, the intermediate elbow lever 358 is turned in the direction for depressing its upper arm into engagement with the lower arm of the releasing elbow lever 336, thereby releasing all of the number keys. The depressed shifting keys remain depressed until 50 the rocking frames 15 and 29 have completed their forward movement. The locking mechanism of the shifting keys is so constructed that the zero key 87 cannot be held

down by the adjacent locking plate, as shown in Fig. 11, because the depression of the same is necessary only during the backward movement of the rocking frames.

Key interlocking mechanism.

In order to produce a correct register and record of the numbers, each column of number keys is provided with a locking mechanism which prevents more than one key in 75 each of these columns from being held in a depressed position at the same time. This locking mechanism is best shown in Figs. 3, 4, 8, 14, and 16, and is constructed as follows:

365 represents a number of tumblers or 80 blocks arranged in longitudinal rows on the bottom of the keyboard, each row being adjacent to the right side of the stems of a respective row of number keys. These tumblers are capable of a longitudinal movement with reference to the column of keys and each set of tumblers is guided on a rod 366 which is supported on the keyboard bottom. Each of the tumblers is provided with a convex upper side which preferably slopes 85 or inclines from its highest central part toward the front and rear sides of the tumbler, in the form of an inverted letter V. The longitudinal movement of the tumblers is limited by front and rear stops 367, 368, 90 95 which are engaged by the front and rear tumblers and which also serve to support the guide-rod 366 on the bottom 42, as shown in Fig. 8. The stem of each number key is provided on the side opposite to its locking plate 100 327 with a follower or spreading head 369. The heads of the intermediate keys have a convex underside which preferably inclines from its lowest central part to the front and rear sides of the head in the form of the 105 letter V.

Each of the spreading heads, except the foremost and rearmost is arranged over the space between two tumblers. The heads of the foremost and rearmost keys are arranged 110 in front and in rear of the foremost and rearmost tumblers and these heads are inclined only on the side facing the adjacent tumbler, as shown in Fig. 8.

Upon depressing a key in any one of the 115 columns of number keys, the spreading head of this key engages with the tumblers on opposite sides thereof and crowds the tumblers in front of the head forwardly and those in rear of the head rearwardly. When 120 the shifting head has been depressed to its fullest extent, the foremost tumbler bears against the front stop 367, and the rearmost tumbler bears against the rear stop 368, and the slack between the several tumblers is 125 fully taken up.

In Fig. 8, key number 5 is shown depressed fully and the slack between the tumblers is taken up, in which position of the key its shoulder 329 is engaged by the 130

catch of the adjacent locking-plate and is prevented from rising. If key number 5 was depressed erroneously, and the correct key, for instance, number 3 is subsequently 5 depressed, this correct key moves downwardly idly until it engages or nearly engages the adjacent tumbler, and when the correct key reaches this position, its releasing cam or convex face engages with the adjacent locking-plate and shifts the same out 10 of engagement from the locking shoulder 329 of the depressed key number 5, as shown in Fig. 4, thereby releasing this key and permitting the same to rise. During the continued downward movement of the correct key number 3, the spreading head of 15 the same moves downwardly between the adjacent tumblers and shifts the same so as to take up the slack between them. When the correct key reaches the end of its downward movement, the same is locked in this position by the adjacent locking plate in the same manner in which key number 5 was 20 previously locked.

25 The slack between the several tumblers is only sufficient to permit of the full depression of one key at a time and the tumblers are so constructed that when two keys are depressed simultaneously these keys are arrested in their downward movement before 30 their locking shoulders are engaged by the locking plate.

By this means, any one key in a column may be depressed and locked in its depressed position and if an incorrect key has been depressed, the same is released by the subsequent depression of the correct key and the correct key is in turn locked in a depressed position, but the locking of two keys at the same time in a depressed position is prevented.

It is sometimes desirable to depress several of the shifting keys simultaneously and lock the same in a depressed position. In 45 the machine as organized no more than three shifting keys require to be depressed and locked at the same time. In order to prevent more than three shifting keys from being locked in a depressed position at the same time, the following mechanism is provided:—

370 represents a number of tumblers which are arranged in a longitudinal row below the stems of the shifting keys and each of 55 which is secured to the lower end of a flat spring 371 depending from the underside of a supporting bar 372. Each of these tumblers has the form of an upwardly tapering wedge, as shown in Fig. 9, and is capable 60 of swinging lengthwise of the column of shifting keys but is held against transverse movement by arranging the depending springs so that their flat sides extend transversely. 373, 374 represent front and rear 65 stops arranged in front and in rear of the

foremost and rearmost tumblers 370. 375 represents a number of followers or spreading heads one of which is secured by a flat spring 376 to the lower end of the stem of each shifting key. Each of these heads is 70 preferably cylindrical in form and is capable of swinging lengthwise of the column of shifting keys, but is held against lateral movement owing to the transverse arrangement of the flat supporting spring. Upon 75 depressing any one of the shifting keys its head moves downwardly between the adjacent tumblers and shifts the same forwardly and backwardly from opposite sides of the spreading head. The front and rear 80 stops 373, 374 are so arranged that the slack between the several tumblers is sufficient to allow of full depression of three shifting keys.

As shown in Fig. 9, three keys are 85 depressed fully and their followers or spreading heads have been moved between the adjacent tumblers so that the several tumblers bear against each other and against the depressed followers or heads and against the front and rear stops 373, 374, thereby taking 90 up all of the slack between the tumblers. In order to lock these three keys in a depressed position, the same must be depressed simultaneously. If an additional key is depressed, as shown in Figs. 5 and 9, this fourth key is free to move downwardly without disturbing the previously depressed keys until its follower or head engages or nearly 95 engages with the adjacent tumblers and when this fourth key reaches this position its releasing cam engages with the adjacent locking plate 327 and deflects the same, as shown in Fig. 5, thereby disengaging the plate from all of the previously depressed 100 keys and causing them to rise simultaneously.

It will thus be seen that by this means three keys can be locked in a depressed position and if an error has been made in the 110 depression of one or more of the keys, the subsequent depression of the correct key or group of three keys permits the release of the previously depressed incorrect keys and the locking of the correct keys in a depressed 115 position. If it is desired to permit of locking more or less than three shifting keys in a depressed position, the slack space between the several tumblers must be adjusted accordingly.

Instead of supporting the tumblers of the shifting keys from the top, as shown in Figs. 5 and 9, the same may be supported by flat springs 377 from the bottom, as shown in Fig. 10. If desired the tumblers and followers of the shifting keys may have the form of spheres, as shown at 378, 379, in Fig. 10.

Any suitable form of platen and paper feeding mechanism may be employed, but as the specific mechanism shown and de- 130

scribed in the parent application and claimed in another divisional application Serial No. 242,395, forms no essential part of the invention sought to be protected by the present application, this mechanism will not be described in detail.

I claim:

1. In a calculating machine, the combination of an accumulator, a printing device for printing digits accumulated by said accumulator, a plurality of keys each of which is movable from normal to operative position and which when moved to operative position will automatically remain therein for controlling said accumulator and said printing device, a hand-controlled operation-controlling member for operating said accumulator and printing device according to the control of said keys, and means cooperative with said keys so that any one but only one of said keys may be in operative position at any one time.

2. In a calculating machine, the combination with accumulating mechanism, of number keys for controlling the amounts accumulated on said accumulating mechanism, a total key for controlling printing of the amount standing on said accumulating mechanism, a plurality of functional keys for determining the character of the operations of the machine, and means whereby the depression of certain of said functional keys renders the total key inoperative.

3. The combination with a key-controlled registering mechanism, of a locking device which is constructed to hold any one of the keys when shifted and which releases the key upon shifting another and in turn holds the latter in a shifted position, and mechanism whereby the shifting of more than one key at a time to controlling position is prevented.

4. The combination with a registering mechanism provided with a number of operating keys, of a locking device which is constructed to hold a group of said keys when shifted and which releases the group of keys upon shifting another key or keys and in turn holds said subsequently shifted key or keys, and a separate locking mechanism whereby the shifting of more than the predetermined number of keys is prevented, substantially as set forth.

5. In a calculating machine, the combination of an accumulator, a reciprocatory actuator for actuating said accumulator, a plurality of depressible controlling keys for controlling the reciprocatory movements of said actuator, and means for preventing the depression of more than a predetermined plurality of said keys at a time irrespective of whether said keys are or are not adjacent to each other, said predetermined plurality being less than the total number of said controlling keys.

6. In a calculating machine, the combination of an accumulator, a reciprocatory actuator for actuating said accumulator, a plurality of depressible controlling keys for controlling the reciprocatory movements of said actuator, means for preventing the depression of more than one of said controlling keys at a time, and means whereby each key is locked in depressed position when depressed and whereby the depression of a second key releases the key previously depressed.

7. In a calculating machine, the combination of an accumulator, a reciprocatory actuator for actuating said accumulator, a plurality of depressible controlling keys for controlling the reciprocatory movements of said actuator, means for preventing the depression of more than a predetermined plurality of said controlling keys at a time, said predetermined plurality being less than the total number of said controlling keys, and means whereby each key is locked in depressed position when depressed and whereby the depression of a second key releases the key previously depressed.

8. In a calculating machine, the combination with the accumulating mechanism thereof, of a plurality of rows of number keys each of which keys may be moved from normal inoperative to operative position for controlling said accumulating mechanism, means for preventing more than one key of each row being moved from inoperative to operative position at a time, an operating member, a total key, and mechanism whereby the operation of said operating member or of said total key effects the return to normal position of any of said number keys which may have been moved to operative position.

9. In a key-controlled machine, the combination of a plurality of rows of manipulative controlling members, each of which manipulative members is movable from normal to operative position; means individual to each of said rows for preventing more than a single one of the manipulative members of the respective row from being in operative position at any one time, and permitting a correction to be made in the setting of said manipulative members; and operating mechanism for operating said machine according to the final setting of said manipulative members, and for effecting restoration of said manipulative members to normal position.

10. In a key-controlled machine, the combination of a plurality of rows of manipulative controlling members, each of which manipulative members is movable from normal to operative position, the movement to operative position of any one of said manipulative members of a row of said members operating to effect the return of any manipulative member of the same row which has

been previously moved to operative position; means individual to each of said rows for preventing more than a single one of the manipulative members of the respective row 5 from being in operative position at any one time; and operating mechanism for operating said machine according to the final setting of said manipulative members and for effecting restoration of said manipulative 10 members to normal position.

11. In a calculating machine, the combination of a plurality of sets of accumulators, each of said sets of accumulators comprising a plurality of accumulators of successive 15 denominational orders, one of said sets of accumulators comprising a plurality of accumulators of like denominational orders to a plurality of accumulators of another of said sets; a plurality of key mechanisms one 20 key mechanism for each set of a plurality of said sets of accumulators for controlling accumulating on the same, each key mechanism comprising a plurality of rows of compressible number keys; mechanism for preventing 25 more than one of said keys in each row being in depressed position at any one time; and operating mechanism common thereto for operating a plurality of said sets of accumulators according to the control of 30 the depressed keys of their respective key mechanisms.

12. In a key mechanism, the combination of a plurality of controlling keys each movable from normal to effective position, and 35 a plurality of special keys each movable from normal to effective position, the construction and arrangement being such that said controlling keys automatically remain in effective position if moved thereto while 40 all of said special keys are in normal position, and that each of said special keys when moved to effective position automatically remains in effective position and may render said controlling keys incapable of automatically 45 remaining in effective position, and that only a predetermined number of said special keys may be in effective position at any one time.

13. In a machine, the combination of a 50 plurality of differentially movable members; a plurality of rows of keys, one row for each member of a plurality of said members for differentially controlling the movements thereof; and movable means individual to each of said rows and comprising a member having a plurality of locking elements, each of said elements co-operative with a respective one of the keys of the respective row for locking the same in a depressed position when depressed, and each movable means being operative to prevent more than one key of the respective row being in depressed position at any one time.

14. In a key-controlled machine, the combination of a plurality of manipulative 60

members, each of which manipulative members is movable from normal to operative position; means for preventing more than a single one of said manipulative members from being in operative position at any one 70 time, and permitting a correction to be made in the setting of said manipulative members; and operating mechanism for operating said machine according to the final setting of said manipulative members and for 75 effecting restoration of said manipulative members to normal position.

15. In a key mechanism, the combination of a plurality of setting keys; a device for detaining any of said keys in set position 80 when set, said keys and device being so correlated that the depression of any key automatically effects the release of any previously depressed key of said plurality and effects the detaining of the key last depressed; means for releasing the key last depressed from said detaining device; and means for preventing more than one key being simultaneously detained in set position.

16. In a key mechanism, the combination with operating mechanism; of a plurality of rows of settable keys movable from inoperative to operative position; locking mechanism individual to each of said rows of keys for detaining any of said keys in operative position when set, and operable by any of said keys to release any detained keys of the same row from the respective locking mechanism; universal means operable by said operating mechanism for effecting 100 the release of any detained keys of said plurality of rows; and means whereby only one of said keys in each of said rows may be detained in set position at a time.

17. The combination of mechanism to be 105 controlled; a group of controlling members for controlling the said mechanism each of said controlling members being movable from inoperative to operative position for effecting such control, and means for preventing more than a predetermined plurality of said members from being in operative position at any one time irrespective of whether said keys are or are not adjacent to each other, and permitting any of said members not exceeding in number said predetermined plurality to be in operative position at any one time.

18. In a key-controlled machine, the combination of a row of controlling keys, each 120 of which keys can be moved from normal to operative position; and means for preventing the movement to operative position at any one time of more than a predetermined plurality of the keys of said row, which plurality may include any keys of the row not exceeding in number the plurality predetermined.

19. In a key mechanism, the combination of a plurality of setting keys; means for de- 130

- taining said setting keys in set position when set and being operable by any of said keys for releasing any other of said keys detained in set position; and means for preventing the simultaneous depression to set position of more than a predetermined plurality of said keys irrespective of whether said keys are or are not adjacent to each other.
- 10 20. In a key-controlled mechanism, the combination of a plurality of rows of controlling keys, each of which keys is movable from normal to operative position; a plurality of shifting keys, each of said shifting keys being movable from normal to operative position, the movement to operative position of any shifting key of a plurality of said shifting keys effecting the return to normal position of any of said
- 15 controlling keys which may be in operative position; and means for preventing more than a predetermined number of said shifting keys being in operative position at any one time.
21. In a key-controlled machine, the combination of a plurality of rows of manipulative members each of which members may be moved from normal to operative position, means individual to each of said rows of manipulative members for preventing more than one of said manipulative members of the respective row being in operative position at any one time, a row of manipulative members each of which members may be moved from normal to operative position, means for preventing more than a predetermined plurality of the manipulative members of the last said row being in operative position at any one time, and common operating means for effecting return to normal position of any of said manipulative members which may have been moved to operative position in any of said rows.
